Primary Examiner — Cynthia R Underwood(57) **CLAIM**

The ornamental design for a cake pop carrier, as shown and described.

DESCRIPTION

FIG. 1 is a front view of a cake pop carrier showing my new design;

FIG. 2 is a rear view of the cake pop carrier;

FIG. 3 is a right side view of the cake pop carrier;

FIG. 4 is a left side view of the cake pop carrier;

FIG. 5 is a top view of the cake pop carrier;

FIG. 6 is a bottom view of the cake pop carrier; and,

FIG. 7 is a top front side perspective view of the cake pop carrier.

The broken lines in FIG. 7 are illustrative of environmental structure forming no part of the claimed design.

1 Claim, 6 Drawing Sheets
